UNITED STATES PATENT OFFICE.

JOHN W. HURLEY, OF PORTLAND, OREGON, ASSIGNOR OF ONE-HALF TO
HENRY CLAY JORDAN.

MEAT-TENDERER.

No. 857,568.

Specification of Letters Patent.

Patented June 18, 1907.

Application filed August 18, 1906, Serial No. 331,165.

To all whom it may concern:

Be it known that I, JOHN WESLEY HURLEY, a citizen of the United States, and a resident of Portland, in the county of Multnomah and State of Oregon, have invented a new and useful Improvement in Meat-Tenderers, of which the following is a specification, reference being had to the accompanying drawings as constituting a part thereof.

- 10 This invention relates to kitchen implements of the character known as "meat-tenderers," and used to render a steak of meat in a tender and more palatable condition, when to be broiled or fried; and the object of my invention is to overcome certain objectionable features, and to make the device, as a whole, more simple and convenient to manipulate.
- 20 To this end my invention comprises oppositely disposed, hingedly connected jaws, the hinges being so arranged that the two jaws may readily be separated for the purpose of cleansing my device. Furthermore I provide lever-like means, whereby the two jaws
- 25 may be compressed together, and by which the necessity for fastening my device to a table, to facilitate its use, is done away with. The arrangement and operation of my device being as illustrated in the drawings above referred to, and hereinafter described.

30 In the drawings: Figure 1 is a perspective of my device, the upper jaw being raised to the position permitting a steak of meat to be placed on the lower jaw; Fig. 2 is a partial cross-section, showing the staggered arrangement of the teeth of the respective jaws, so as to be able to pass each other, upon the compression of the jaws; Fig. 3 is a partial plan view showing the arrangement of the hinges, whereby the jaws are removably united; Fig. 4 is a partial end view, looking in the direction of the arrow shown in Fig. 3, and illustrating the construction of the right-hand hinge-knuckles; Fig. 5 is a sectional detail of the right-hand hinge-knuckle a'' ; and Fig. 6 is a partial longitudinal section illustrating the lever-like means for compressing the jaws.

40 Referring now to the reference letters: The jaws a , b , are cast with teeth c , and hinge-knuckles a' , a'' , b' , b'' . The hinge-knuckles a' , a'' are perforated, and the hinge-knuckles b' , b'' are provided with pintles d , to be inserted in such perforation. Thus the

55 two jaws, a , b , can be separated by moving the same laterally in opposite directions. To prevent the same becoming accidentally displaced, and thus causing the teeth to interfere with each other, I provide retaining means, whereby the lateral separation of the 60 two jaws, on their hinges is prevented until the jaw b is thrown back to the position thereof indicated in dotted outline b^2 in Fig. 4. Such retaining means consist in providing the hinged lug a'' with a laterally projecting arm a^3 made with a pendent lug or shoulder a^4 , arranged to engage with the face of the hinge-lug b'' as illustrated in Figs. 3 and 4. And the hinge-knuckle b'' has a recess b^5 arranged as shown in Fig. 4, so that 70 when the jaw b is thrown into the position shown by the dotted outline (b^2) in Fig. 4, the recess b^5 will become positioned in alignment with the lug a^4 of the arm a^3 , and thereupon the jaws may be separated as mentioned.

75 To provide for the effective compression of the jaws, a , b , upon each other, I make the front end of the jaw a , with hinge-lugs e , in which is pivoted a lever f , comprising an integral pendent arm g , the extremity g' of which is curved inward, so as to be arranged to engage with a shoulder h , formed on the front end of the lower jaw b . Thus by bearing down on the handle of the lever f , the jaws a , b , are compressed with considerable force. In the use of my device, the teeth will perforate the meat compressed between the jaws sufficiently to allow the heat to penetrate the meat more effectively, and the steak may be 90 cooked to the degree desired to render the same juicy and palatable.

80 I claim:

1. In a meat tenderer, the combination of a pair of jaws provided with teeth on their 95 inner faces, and respectively made with hinge joints by which the jaws are separably hinged, means for locking the hinge joints against inadvertent separation, lever-like means pivoted on the front end of one jaw 100 and arranged to engage with the front end of the other, to forcibly compress the jaws.
2. A meat tenderer comprising a pair of jaws provided with teeth on their inner faces, one thereof being made with perforated 105 hinge-knuckles, and the other with hinge-knuckles provided with projecting pintles removably inserted in the perforated hinge.

knuckles; one pair of hinge-knuckles being provided with means preventing inadvertent disengagement and consisting in one member of said pair of hinge-knuckles being made 5 with a rigid projecting arm having a lug on its extremity arranged to engage with the other member, and the latter having a recess

arranged to allow the lug to pass when brought in alinement therewith.

JOHN W. HURLEY.
